HAIM M. PEREZ, OF NEWPORT BEACH, CALIFORNIA

LAND AND WATER AEROPLANE

Application filed May 31, 1928. Serial No. 281,831.

My invention is a land and water aeroplane of a type adapted for propulsion through the water in the manner of a boat.

An object of my invention is the construction of an aeroplane with a fuselage resembling the hull of a boat in which may be mounted a motor with a propeller for propulsion as a boat and with a steering rudder for use in the water. The hull is provided with wheels so that it may be operated on land in the usual manner.

Another object of my invention is mounting a propeller on the forward or bow end of the fuselage or boat hull and having surmounted on this hull a superstructure with a second motor in the forward end thereof; and on top of the superstructure there is a turret with a motor and a propeller mounted on the bow end thereof.

Another object of my invention is mounting on the boat hull fore and aft monoplane wings arranged in tandem and connected to the turret or superstructure to provide a pair of biplane wings, these wings being tiltable for use in vertical direction of flying.

Another object of my invention is the mounting of a steering rudder on top of the turret, this having a vertical blade which may be turned at various angles to give direction horizontally.

Another object of my invention is to form a parachute construction by swinging an upper flap of a fore and aft set of wings forwardly and backwardly to engage the biplane wings and form with side plates connected to the outer portion of the wings a parachute structure. Another object of my invention is in the controls for the various movable parts of the aeroplane.

My invention is illustrated in the accompanying drawings in which:

Fig. 1 is a side elevation,

Fig. 2 is a plan,

Fig. 3 is a front elevation,

Fig. 4 is a horizontal section substantially on the line 4—4 of Fig. 1 of the lower part of the hull,

Fig. 5 is a horizontal section substantially on the line 5—5 of Fig. 1 through the super-

structure, showing the controls for the parachute flaps,

Fig. 6 is a vertical section on the line 6—6 of Fig. 2 in the direction of the arrows, through the turret, showing the control for the elevation steering wings and for the rudder,

Fig. 7 is a detail section on the line 7—7 of Fig. 2 showing the attachment of the parachute flaps to the main portion of the wing.

The boat hull 11 forms the main structure, and on this there is built a superstructure 12, and on top of the superstructure there is a turret 13. The hull has a fore and aft deck 14, the superstructure has a deck 15, and the turret has a deck 16.

The hull has a pair of supporting wheels 17 mounted on an axle 18 extending through the hull, and at the stern has a rudder post 19 with a castor type of wheel 20 on the bottom. The rudder post carries a large rudder 21 for use in steering when traveling in the water and to act as a vertical fin or as a steering rudder when flying. A water propeller 22 at the stern of the hull is operated by a motor 23. There are three propellers 24, 25 and 26 mounted on the front or bow end of the hull 11, the superstructure 12 and the turret 13 respectively. Each motor has a separate engine designated 27.

The hull has a forward and rearward set of wings 28 and 29, these being preferably of a monoplane type and fixedly secured to the hull. Each wing has a parachute flap 30 and 31. The flap 30 on the forward wing is connected to a pintle pin 32 or other suitable hinge adjacent the trailing edge of the wing, and the flap 31 has a hinge connection 33 to the forward edge of the trailing wing. The wing structures have a recess or hollow structure designated as 34 (note Fig. 7) in which the flaps are housed for ordinary flying. The flaps are held in flying position by means of nubs 35 engaging in sockets 36, the nubs being outwardly pressed by springs 37.

A set of control wings 38 for vertical direction of movement are constructed with a shaft 39 extending through the turret from side to side and having diagonal bracing 40

connected thereto; and attached to this bracing there are wings 41 forming a biplane structure. The shaft 39 has a worm wheel 42 thereon which may be rotated by a worm 43 on a worm shaft 44, this latter having a hand control wheel 45 (note Fig. 6), this being mounted in the turret. By this construction by rotating the shaft 44 the shaft 39 may be oscillated to change the inclination of the 10 control wings 38 and thus provide for the steering in vertical direction of flying.

The rudder construction for horizontal direction designated 46 is mounted on a vertical shaft 47 extending through the deck 16 15 of the turret 13; and on the lower end of this shaft there is a worm wheel 48 which meshes with a worm 49 on a control shaft 50 operated by a hand wheel 51 (note Fig. 6). Surrounding the rudder there is a guide cage 52 20 having a horizontal ring 53 at the top and 54 at the bottom adjacent the deck, with posts 55 extending upwardly from the deck and supporting the ring 53. The rudder has notches 56 to guide the rudder relative to the 25 rings 53 and 54. By this construction it will be seen that by operating the hand wheel 51 the rudder 46 may be turned on a vertical axis.

The control for the rudder 21 comprises a 30 bevel pinion 57 mounted on the rudder post 19 engaging a bevel wheel 58 mounted on the steering shaft 59, this shaft having a suitable control wheel 60. This control is mounted in the hull 11 and by turning the wheel 60 the 35 rudder 21 may be operated or the castor wheel 20 used for steering when on the land. The rudder 21 may be utilized for steering when traveling on the water or when flying.

The parachute arrangement comprises a 40 pair of triangular, vertical fins or plates 61 which are secured to the ends of the wings 28 and 29, being attached to the rear end of the forward wing 28 and the forward end of the rear wing 29; these fins are preferably attached to the pintles 32 and 33. The apexes of the fins are secured to the ends of the shaft 39. A forward set and a rear set of cables 62 and 63 are secured to the forward edge of the front parachute flaps 30 and the rear parachute flaps 31 respectively. These cables pass through sets of pulley blocks 64 mounted in the diagonal bracing 40. These cables pass through openings 65 in the turret.

An operating drum 66 is mounted on the 55 shaft 67 extending longitudinally in the superstructure 12. This shaft is driven by a countershaft 68 and positioned either above or below the drum and driving the drum shaft through gears 69. The cables 62 and 60 63 from each side of the elevator wings 38 pass over sets of pulley blocks 70 and are wound on the drum 66. Therefore by operating the countershaft 68 the drum 66 may be rotated so as to exert tension on the 65 forward and rearward set of cables 62 and

63, which action pulls the front parachute flap upwardly, pivoting on the rear pintle 32 and the parachute flap 31 also upwardly, the ends of these flaps coming into engagement with the lower wing of the control wings 38, as shown in dotted lines of Fig. 1. The tension on the cables holds these flaps in place.

The wing structure together with these flaps and the fins 61 act as a parachute in the descent of the aeroplane for landing, the air being in effect caught between the two pockets on each side of the hull of the superstructure. After the aeroplane has landed the flaps may be manually returned to position for flying by unwinding the cables and allowing the flaps to be returned to their proper position in the recesses 34 of the main wing structure. The drum 66 may be held stationary in any desired position by utilizing a pawl to engage the gear wheel 69 in any suitable manner.

Various changes may be made in the principles of my invention without departing from the spirit thereof, as set forth in the 90 description, drawings and claims.

I claim:

1. An aeroplane having a boat-like hull with a fore and aft set of wings in tandem, elevator wings positioned between and above 95 the main wings to rock on a horizontal axis, and a steering rudder mounted on a vertical axis above the elevator wings.

2. An aeroplane having a boat-like hull with a fore and aft set of wings in tandem, 100 a superstructure and a turret thereabove, an elevator set of wings mounted on a rocking transverse shaft, and a steering rudder mounted on a vertical shaft extending upwardly from the turret.

3. An aeroplane having a fuselage with a forward and a rear set of wings in tandem, each wing having a tiltable flap on the top, the flap on the forward wing tilting backwardly and the flap on the rearward wing 110 tilting forwardly, and means to tilt said flaps toward each other to act as a parachute.

4. An aeroplane as claimed in claim 3, vertical fins connected to the outside of the wings and forming with the flaps an air 115 pocket.

5. An aeroplane having a boat-like structure with a fore and aft set of wings in tandem, elevator wings mounted above and between the wings, the forward wings having a flap to tilt backwardly and the rearward wings having a flap to tilt forwardly to engage the elevator wings, forming with the body and the elevator wings a parachute 120 structure.

6. An aeroplane as claimed in claim 5, the elevator wings having a rocking shaft and a fin secured to the rear end of the forward wing and the forward end of the rear wing 130

and to the said shaft forming with the flap
and the body structure air pockets.

7. An aeroplane having a boat-like hull,
a superstructure mounted thereon, a turret
mounted on the superstructure, the nose of
the superstructure being positioned aft of
the bow of the boat hull and the nose of the
turret being positioned aft of the position
of the nose of the superstructure, a propeller
10 mounted on the bow end of the hull and on
the nose of the superstructure and turret,
said propellers being mounted on substantially
horizontally horizontal shafts, and said shafts being in
the same vertical plane, together with a plu-
15 rality of pairs of wings, a lowermost pair
being situated on opposite sides of the turret
and an intermediate pair on opposite sides
of the superstructure.

In testimony whereof I have signed my
20 name to this specification.

H. M. PEREZ.
